UNITED STATES PATENT OFFICE

129,928

DESIGN FOR A PITCHER-SPOUT PUMP

Elmer D. Pellegrin, Woodstock, Ill., assignor to
Geo. D. Roper Corporation, Rockford, Ill., a
corporation of Illinois

Application June 9, 1941, Serial No. 101,354

Term of patent 7 years

To all whom it may concern:

Be it known that I, Elmer D. Pellegrin, a citizen of the United States, residing at Woodstock, in the county of McHenry and State of Illinois, have invented a new, original, and ornamental design for a Pitcher-Spout Pump, of which the following is a specification, reference being had to the accompanying drawing, forming part thereof.

In the drawing:

Fig. 1 is a front elevational view of a pitcher-spout pump showing my new design;

Fig. 2 is a side elevational view thereof, and

Fig. 3 is a top plan view thereof.

I claim:

The ornamental design for a pitcher-spout pump, substantially as shown.

ELMER D. PELLEGRIN.
